UNITED STATES PATENT OFFICE

115,146

DESIGN FOR AN AUTOMOBILE BUMPER

Jeronimo Falcon, Buenos Aires, Argentina, assignor to Auto-Rapid Products Corporation, a corporation of New York

Application March 27, 1939, Serial No. 83,845

Term of patent 7 years

To all whom it may concern:

Be it known that I, Jeronimo Falcon, a citizen of Spain, residing at Buenos Aires, Argentina, have invented a new, original, and ornamental Design for an Automobile Bumper, of which the following is a specification, reference being had to the accompanying drawing, forming part thereof.

I claim:

The ornamental design for an automobile bumper, as shown.

JERONIMO FALCON.
